CHARLES W. MEVES AND FREDERICK G. HERRMANN, OF SHEBOYGAN, WISCONSIN,
ASSIGNORS TO SHEBOYGAN COUCH COMPANY, OF SHEBOYGAN, WISCONSIN, A
CORPORATION OF WISCONSIN.

DAVENPORT.

1,367,621.

Specification of Letters Patent. Patented Feb. 8, 1921.

Application filed December 6, 1919. Serial No. 342,999.

To all whom it may concern:

Be it known that we, CHARLES W. MEVES and FREDERICK G. HERRMANN, citizens of the United States, and residents of Sheboygan, in the county of Sheboygan and State of Wisconsin, have invented new and useful Improvements in Davenports, of which the following is a description, reference being had to the accompanying drawings, which

10 are a part of this specification.

The invention relates to davenports of the type convertible into a bed.

In devices of this character it is usual to ship the frame and the spring mattress 15 structure in knockdown condition, the parts being set up to form the completed davenport after arrival at the shipping point. In view of the fact that this setting up is generally done by unskilled workmen, it is important that this problem of assembly be 20 made as simple as possible. To this end we have provided a construction in which all the moving parts are connected to side plates which may be quickly attached or detached 25 from the frame of the davenport by an unskilled workman.

A further object of the invention is to provide a davenport with a fixed back and to house all the parts connecting and actuating the bed sections out of sight at the sides of and below the seat. Thus the usual 30 preliminary lifting of the back is obviated, the opening of the davenport is greatly simplified, the operator is relieved of any danger from a falling back and the appearance of the davenport is improved.

The invention further consists in the several features hereinafter set forth and more particularly defined by claims at the conclusion hereof.

In the drawings: Figure 1 is an end view of a bed davenport embodying the invention, shown in closed position, one end thereof being removed; Fig. 2 is a view similar to Fig. 45 1, showing the davenport converted into a bed; Fig. 3 is a detail front end view of the davenport converted into a bed, parts being broken away and parts being shown in section; Fig. 4 is a detail view of one of the 50 plate fasteners.

In the drawings, the numeral 4 designates an end frame, the other similar end not being shown, but both connected to a fixed back 5.

A pair of plates 6 are detachably connected to the end frames by means of bolts 7 and hooks 8 secured to the side frames. The bolt 7 passes through an elongated slot 9 in each plate and carries a wing nut 10 to clamp the plate against the adjacent end 55 frame and the hook 8 is passed through an enlarged opening 11 in the plate and engages the plate at the upper end of the opening. All the moving parts of the davenport are carried by these plates and their connection with the end frames are so simple that any unskilled workman can readily set up the davenport.

A swinging front rail 12 is mounted on a pair of rail irons or swinging arms 13 pivotally mounted on pins 14 carried at the lower front corners of the plates. The front rail 12 is capable of swinging on these pivotal connections from its upright position shown in Fig. 1 to its inclined position 70 shown in Fig. 2, its movement being limited by means of links 15 pivotally connected at one of their ends to the arms 13 and having slots 16 in their other ends in which stop pins 17 are mounted, said pins being carried 75 by the plates 6.

Each front rail iron 13 has a forwardly extending projection 18 at its upper end which is pivotally connected by a pin 19 to the lower portion of a bracket 20 secured to 85 the frame of the seat member or cushion 21 near the front end thereof. On the pivotal connections thus formed the seat may be inverted from its upright position shown in Fig. 1 to its inverted position shown in Fig. 90 2. This simple swinging movement of the seat to its inverted position by the operator is utilized to bring the bed section of the davenport from a position beneath the seat to extended operative position in the manner 95 hereinafter described.

The seat member 21 has brackets 22 secured to its frame near its rear end. A bed section 23 is connected to said brackets 22 by means of pins 24 which are slidably 100 mounted in inclined slots 25 communicating with short substantially horizontal slots 26 in said brackets. Another bed section 27 is connected to the first bed section 22 through an intermediate hinge section including links 105 28 forming hinge members between the sections 27 and 22. The links 28 are pivotally mounted intermediate their ends upon pins

29 pivotally supported in the upper portions of the brackets 20 and secured to a transversely extending brace bar 30. The bed sections have the usual spring fabric supporting structure.

5 The rear portion of the bed section 27 is pivotally connected to one of the ends of legs 31. These legs 31 each have pins 32 and 33 spaced apart and slidably movable in 10 slots 34 and 35 respectively in the plates 6. The slots 34 and 35 are so positioned and formed as to permit the legs 31 being substantially vertically disposed when the pin 32 is at the rear end of the slot 34 and the 15 pin 33 is at the upper end of the slot 35, in which instance stops 36 on the plates prevent forward movement of said legs, as shown in Fig. 2. It will also be noted that the upper end of the slot 35 extends rearwardly at an angle from the remainder of 20 this slot, the bend 37 forming a temporary stop for the pin 33 as hereinafter described.

The parts are so mounted that when they 25 are in closed position the bed sections 23 and 27 are disposed beneath the seat and the other parts at the sides of and beneath the seat. The seat section in its closed position is supported at its forward end upon the front rail 12 and at its rear end on rests 38 30 at the back of the davenport.

To change the device to its bed form the operator grasps the rear end of the seat member or cushion 21 and draws it upwardly and forwardly and over to inverted 35 position, during which movement it swings on the arms 13 and at the same time these arms swing about the pins 14 and at the same time also this swinging movement moves the section 23 and the links 28 with it, 40 thereby carrying the section 27 upwardly, its movement being guided by the movement of links or legs 31 in the slots 34 and 35, and when the pins 33 reach the bend 37 and the arms 13 have been stopped in their 45 swinging movement by the pins 17 reaching the ends of the slots 16, then, as the seat 23 moves over to its final position, the links 28 are swung to a horizontal position in line with the section 27 while the pin 24 reaches 50 the upper end of the slot 25 and the pins 32 and 33 reach the ends of their movement, the parts being then in the position shown in Fig. 2. In this position the bed sections are supported at the points 14, 17, 29, 24 and 55 by the legs 31 and the usual foldable front legs 39.

To return the parts to closed position the movement of the seat section is reversed from that of opening, whereby the movements of the parts connected therewith are reversed from that previously described and the bed sections are swung into the position shown in Fig. 1. During this closing movement the initial swinging movement of the 60 links 28 is effected by temporarily stopping

the movement of the pin 33 by its position in the upper end of the slot 35 and also by the fact that at this time the seat section is swinging about the point 19 and section 23 is turned down to a position adjacent the 70 seat and the links 28 and legs 31 coöperate in moving the section 27 to inoperative position beneath the seat.

It is to be understood that these bed sections are of suitable length for a bed and 75 that the width of the bed is determined by the ends of the bed sections when in extended position.

We desire it to be understood that this 80 invention is not limited to any specific form or arrangement of parts except in so far as such limitations are specified in the claims.

What we claim as new and desire to secure by Letters Patent is:

1. In a bed davenport, the combination 85 of a seat member pivotally mounted near the front thereof and adapted to be inverted, a bed section connected to the seat member, a second bed section connected to the first bed section and raised by the movements thereof, supporting links for the rear end of the second bed section, each link carrying spaced pins, and converging guide slots for said pins for guiding the movement of said links to an upright position when the seat is inverted. 95

2. In a bed davenport, the combination 100 of a seat member, forwardly swinging arms on which the seat member is pivotally mounted, a bed section carried by the seat member, a second bed section connected to the first bed section and raised by the movement thereof, supporting links for the rear end of the second bed section, spaced pins on each of said links, and converging guide 105 slots for said pins to cause movement of the links to an upright position when the seat is inverted.

3. In a bed davenport, the combination, 110 with a frame having end walls, of a metal plate detachably secured to each end wall, forwardly swinging arms pivotally mounted on said plates, a seat section pivotally mounted on the free ends of said arms, a bed section carried by the seat, a second bed section connected to the first bed section and raised by the movements thereof, supporting links for the rear end of the second bed section, and spaced pins on each of said links, said plates having guide slots therein 115 receiving said pins to guide the movements of the links. 120

4. In a bed davenport, the combination 125 of side frames, a fixed back, a pair of swinging arms carried by said side frames, means for limiting the swinging movement of said arms, a seat member swingingly mounted on the outer ends of said arms, hinge links having their intermediate portions pivotally connected to the seat member, slotted brack- 130

ets secured to said seat member, a bed section carrying pins slidably mounted in the slots of said brackets and also pivotally connected to one of the ends of said hinge links,
5 a second bed section connected to said hinge link at one end, supporting links pivotally connected to the other end of said second bed section, each supporting link carrying spaced pins, and converging guide slots en-

gaging said pins to control the movement of 10 said links.

In testimony whereof, we affix our signatures, in presence of two witnesses.

CHARLES W. MEVES.

FREDERICK G. HERRMANN.
